UNITED STATES PATENT OFFICE.

JOHN E. TEALL, OF ROCHESTER, NEW YORK, ASSIGNOR TO LANGSLOW, FOWLER COMPANY, OF ROCHESTER, NEW YORK, A CORPORATION OF NEW YORK.

DESIGN FOR A CHAIR.

SPECIFICATION forming part of Design No. 36,663, dated December 1, 1903.

Application filed October 31, 1903. Serial No. 179,412. Term of patent 3½ years.

To all whom it may concern:

Be it known that I, JOHN E. TEALL, a citizen of the United States, residing at Rochester, in the county of Monroe and State of New York, have invented a new, original, and ornamental Design for Chairs, of which the accompanying drawing is a representation.

The figure is a perspective view of a chair, showing my new design.

What I claim as new, and desire to secure by Letters Patent, is—

The ornamental design for a chair as herein shown.

JOHN E. TEALL.
